UNITED STATES PATENT OFFICE.

ALBEN E. LUNDELL, OF NEW YORK, N. Y., ASSIGNOR, BY MESNE ASSIGNMENTS, TO
WESTERN ELECTRIC COMPANY, INCORPORATED, A CORPORATION OF NEW YORK.

MACHINE-SWITCHING TELEPHONE-EXCHANGE SYSTEM.

1,337,710.

Specification of Letters Patent. Patented Apr. 20, 1920.

Application filed June 7, 1915. Serial No. 32,618.

To all whom it may concern:

Be it known that I, ALBEN E. LUNDELL, a citizen of the United States, residing at New York, in the county of Bronx and State 5 of New York, have invented certain new and useful Improvements in Machine-Switching Telephone-Exchange Systems, of which the following is a full, clear, concise, and exact description.

10 This invention relates to a telephone exchange system having both manual offices and offices employing machine switching.

Its object is to provide for the transfer of a call from a manual office to a semi-automatic office, and the novelty consists in a circuit arrangement whereby a call originating in a manual office is trunked therefrom to a semi-automatic office and is there extended over automatic selector switches 20 under control of an operator, the sender of such operator being automatically disconnected from the said automatic switches the instant the connector is set upon the wanted line. In case the line is busy, automatic 25 means is brought into play at the connector to operate a visual signal before the manual or originating operator to inform her of this fact, whereupon she so informs the calling subscriber. Preferably this visual signal is 30 the regular supervisory lamp associated with the calling plug of the manual operator's cord circuit, and the automatic means at the connector may consist of an electromagnetic device which causes the supervisory relay 35 controlling such lamp to be operated to cause the lamp to flash.

Referring to the drawings, Figure 1 is a diagram of the cord circuit at the manual switchboard; Fig. 2 is a diagram of the first 40 selector circuit and associated apparatus; Fig. 3 is a diagram of the connector and associated apparatus.

The cord circuit, shown in Fig. 1, is well known in the art, and therefore need not be 45 described in detail. The removal of the receiver by the calling party at substation A⁴ in initiating a call causes the line lamp LL of such line to be lighted at the operator's position. In response to the illumination 50 of this lamp the operator inserts the plug P in the jack J and inquires the number of the wanted party, the energization of the answering supervisory relay SR closing a shunt circuit about the answering supervisory lamp SL to prevent its illumination in

the well-known manner. Upon ascertaining that the desired number belongs to a subscriber whose line terminates in a semi-automatic office, she communicates over an order wire (not shown) with an operator at 60 such semi-automatic office, which operator we will hereinafter term the B operator. This operator will then assign a trunk terminating in a jack J', to be used by the subscriber's operator or A operator, as she 65 will hereinafter be called, and depresses the key 203 of the connecting circuit belonging to the trunk so assigned. The B operator is provided with a number of senders, an idle one of which is adapted to be automatically associated with the connecting circuit (Figs. 2 and 3) of her position, to which the depressed key 203 belongs, upon the depression of such key. She then writes down 70 the number of the wanted line upon her keyboard, which registers this number. After the number has been registered by the sender, the keyboard is freed therefrom, and the sender begins its operation of controlling the automatic switches of Figs. 2 and 80 3. This sending equipment is temporarily associated with the connecting circuit by the leads 236, 212, 207, 208 and 205. For the sake of simplicity, the sending apparatus is not shown, since it is fully disclosed 85 in Patent No. 1,168,319 of January 18, 1916.

The invention will be more readily apparent from a detailed description of the operations involved in setting up a call between substation A⁴, Fig. 1, terminating in 90 a manual office, and substation B², Fig. 3, terminating in a semi-automatic office.

The removal of the receiver by the calling party at substation A⁴ closes the following circuit to light the line lamp LL: free pole 95 of battery, left winding of line relay LR, left armature and back contact of cut-off relay CO, line conductor a, the telephonic apparatus at substation A⁴, line conductor b⁴, inner armature and back contact of cut-off relay CO, right winding of relay LR, to battery. The line relay at its armature and front contact closes the circuit of line lamp LL. The operator upon observing the illumination of the lamp LL inserts the answering plug P into the answering jack J of the calling line, and depresses her listening key LK and inquires the number of the wanted party, the cut-off relay being operated in the usual way to open the circuit 105 110

of the line relay LR and cause the extinguishment of the line lamp LL. The energization of the supervisory relay SR shunts out the supervisory lamp SL of the calling 5 party in the well-known manner. Upon learning the number wanted, which will be assumed to terminate in a connector in a semi-automatic office, the answering or A operator communicates, by means of an 10 order wire in the well-known manner, with a B operator at such office who is provided with a sender by means of which she can direct automatic switching apparatus to connect with the desired line. This operator, which will be called the "cordless" or 15 B operator, informs the A operator over the order wire of the trunk to be used. The A operator thereupon inserts the plug P' into the jack J' of such trunk. In the 20 meantime, the B operator depresses key 203 to move the sequence switch 200 to prepare circuits for causing one of her senders to be temporarily associated with this trunk, which sending apparatus, as has been stated, 25 is not shown in detail.

The sequence switch S² prepares circuits for the first selector S in a manner now well known in the art, (see U. S. Patent 1,105,- 30 811, August 4, 1914). The connector (Fig. 3) and the sender circuits are also provided with sequence switches. The depression of key 203 closes the following circuit to move sequence switch S² to position 2: free pole of the battery, sequence switch motor magnet 35 200, conductor 265, sequence switch spring 201 (1), conductor 202, key 203 to ground. The numbers adjacent the sequence switch contacts indicate the closed positions thereof, they being open in all 40 other positions. The contact spring A, however, is a special contact to insure the full movement of the sequence switch to the next intended stopping position, and the numbers near it indicate the positions wherein this 45 contact is open, it being closed in all the positions not noted.

The sequence switch tables at the left of Fig. 2 and in the upper left-hand corner of Fig. 3 aid in tracing the circuits. In 50 position 2 of sequence switch S², the closure of spring 204 by grounding conductor 205 moves the sender sequence switch into position 2, and the closure of spring 206 bottom grounds conductor 207 which terminates in a fixed contact of the cord finder switch as fully disclosed in said patent. The sender sequence switch in position 2 55 closes the driving circuit of this cord finder switch, and when one of its brushes reaches the said grounded contact connected to conductor 207, the test relay of the cord finder is energized and at its back contact opens the driving circuit of the cord finder switch 60 and thus associates the sender with the 65 trunk. This relay in energizing locks itself

to conductor 208 and sequence switch contact 206 (2-9) which is grounded at spring 204 and contact 232. It may be mentioned at this point that contact 232 permanently grounds spring 204.

The sequence switch S² now waits in position 2 until the operator has written down the number upon the key-board and the sender has recorded such number. When the sender has recorded such number, the 70 sequence switch controlling the same advances and closes a circuit to control the first selecting operation. This circuit will be referred to hereafter as the fundamental 75 circuit. It leads as follows: free pole of the battery, right winding of control relay CR, conductor 210, spring 211 (2), conductor 212, through the stepping relay at the sender, to ground. The relay CR at its left armature and front contact and spring 80 267 (2) advances the sequence switch S² to position 3 to close the circuit of driving magnet P of the selector S, and at its right armature and front contact locks itself directly to conductor 212 over the following 85 path: free pole of the battery, right winding of relay CR, its armature and front contact, conductor 223, spring 229, spring 213 (2), to conductor 212. The circuit for magnet P is as follows: free pole of battery, conductor 216, magnet P, conductor 218, spring 219 (3), conductor 231, left armature and front contact of relay CR, to ground. The magnet P in attracting its armature 90 220 forces the brush shaft 221 into engagement 95 with the constantly rotating driving shaft 222. The selector switch need not be described in detail herein since it is fully 100 described in the patent referred to. The stepping relay at the sender is intermittently 105 operated as the shaft 221 moves upwardly and operates a series of counting relays at the sender which, in conjunction with the set condition of the sender, measures off the extent of travel of the shaft. 110 When a predetermined number of such counting relays has operated, determined by a contact closed in the sender by the operator in writing down on her keyboard the 115 called number, a cut-off relay is operated to open the fundamental circuit just traced, the consequent de-energization of control relay CR opening the circuit of power control magnet P to stop the elevating movement 120 of the shaft 221, which is held elevated in any suitable manner. Considering the 125 operation more in detail, for each contact of the commutator A² passed over, the following circuit is closed in shunt of the stepping relay at the sender: spring 229 (3), conductor 224, contacts of the segment A⁴, brush 226, spring 293 (3) to ground. Assuming 130 that the first brush is the one to be selected, as the brush 226 passes over the first A⁴ interrupter segment, the cut-off relay at the

sender operates, which results in the deenergization of control relay CR. The control relay by opening its left armature and front contact opens the circuit of magnet P whereupon motion of the shaft 221 is arrested. When the brush shaft stops, it is in such a position that the operation of the trip magnet TM will release only the first set of brushes b , b' , b'' upon the continued 5 elevation of the shaft 221, when the power magnet P is again excited. The control relay CR at its left armature and back contact and spring 227 (3) moves the sequence switch to position 4, in which it awaits the 10 completion of the fundamental circuit at the sender preliminary to the next selecting operation. When this circuit is completed, the control relay CR is again energized and at its left armature and front contact and 15 spring 267 moves the sequence switch to position 5, and at its right armature and front contact locks itself to conductor 212 which leads to the stepping relay at the sender as before. The circuit of magnet P 20 is again closed by way of spring 219 (5), and the left armature and front contact of control relay CR. The shaft 221 is thereupon elevated. During the beginning of its movement, the trip magnet TM trips the 25 selected set of brushes. For each segment of the B commutator passed over, the stepping relay at the sender is shunted by way of spring 213 (5) and conductor 253. We will assume that the trunks leading to the 30 desired group of final connectors is the third group in the division of the panel served by the selected set of brushes. Therefore, upon the third operation of the stepping relay, due to its being shunted by the brush 35 227 and B commutator segments, conductor 253, spring 213 (5), the cut-off relay at the sender opens the fundamental circuit, resulting in deenergizing the relay CR. The relay CR at its left armature and front contact 40 opens the circuit of magnet P with the test brush b^2 in contact with a terminal grounded by conductor t^3 below the selected group of trunks, and at its back contact moves the sequence switch to position 6 45 over the following circuit: free pole of the battery, magnet 200, conductors 265, 266, 228, spring 227 (5), left armature and back contact of relay CR, to ground. Due to the closure of spring 211 (6), the relay CR 50 immediately pulls up again and locks itself up to such terminal t^3 over the following circuit: free pole of the battery, right winding of relay CR, right armature and front contact, conductor 223, spring 229 (6), conductors 230, 257, brush b^2 , to grounded test terminal t^3 . At its left armature and front contact, relay CR moves the sequence switch to position 7. In this position the magnet P is energized over the following circuit to 55 elevate the shaft 221: free pole of the bat- tery, conductor 216, magnet P, conductor 218, spring 219 (7), conductor 231, left armature and front contact of relay CR, to ground. As the brush b^2 passes between terminals t^2 the control relay is held up over 60 the following circuit: free pole of battery, spring 251 (7), left winding of said relay, conductor 290, segments of commutator C, brush 225, spring 294 (7), conductors 291, 291, armature and front contact of relay CR to ground. When the brush b^2 reaches test terminal t^2 of an idle trunk, which is indicated by the absence of ground, the relay CR falls back when the brushes b , b' have been accurately centered thereon, 65 which occurs when the brush 225 passes off the segment of the commutator C corresponding thereto. The circuit of magnet P is thus opened at the left armature and front contact of relay CR to stop the switch. This 70 relay at its back contact and spring 227 (7) drives the sequence switch S^2 from position 7 to position 9. The brushes b , b' are now connected to terminals t , t' , leading to the 75 final selector or connector having access to 80 the wanted line.

As soon as relay CR falls back when the brush b^2 arrives on the test terminal t^2 of the idle trunk, it renders the same unselectable to other testing selectors S by the closure of 85 ground thereto as follows: grounded spring 204, conductor 260, spring 259 (7), conductor 292, right armature and back contact of relay CR, conductor 223, spring 229 (7), conductors 230, 257, to test brush b^2 . As 90 95 the sequence switch moves into position 8, this ground leads over the circuit just traced to spring 259 (8), from thence over conductors 258, 257 to said test brush.

During the trunk hunting operation just 100 described, the sender was waiting for the sequence switch S^2 to reach position 9. The fundamental circuit in position 9 is again closed to control the selection of the brush at the connector. Assuming that the number of the wanted line is 455 and that each connector has a capacity of 500 lines, it will 105 be necessary to trip the fifth brush which has access to the lines from 400 to 499. The fundamental circuit to the connector is as 110 115 follows: free pole of the battery (Fig. 3), relay C'R', conductor 311, spring 346 (1), conductor 315, conductor 347, terminal t' , brush b' , conductor 255, spring 233 (9), conductors 262, 256, 212, through the stepping 120 relay at the sender, to ground. The relay C'R' immediately locks itself up directly to the conductor 315 by way of conductor 314, armature and front contact of said relay and spring 313 (1). At its right armature and front contact, relay C'R' closes the following circuit to move the sequence switch S^3 of the connector into position 2: free pole of the battery, magnet 300, conductors 303, 304, spring 305 (1), conductors 125 130

306, 307, conductor 308, right armature and front contact of relay C'R', to ground. In position 2, trunk relay 335 is energized over a circuit by way of spring 348 (2) and locks itself over the following circuit: free pole of the battery, relay 335, left armature and front contact thereof, conductor 302, spring 301 (2), conductor 380, terminal t^2 , brush b^2 , conductors 257, 258, spring 259 (9), conductor 260, to grounded spring 204. The relay 335 at its right armature and front contact moves the sequence switch S³ to position 3 by way of spring 349 (2). In position 3 the high speed magnet H is energized and by attracting its armature 376 forces the brush shaft 350 against the constantly rotating shaft 377. This circuit is as follows: free pole of the battery, magnet H, conductor 309, spring 310 (3), conductors 307, 308, right armature and front contact of relay C'R', to ground. Each time the brush 321 contacts with a segment of commutator A', the stepping relay at the sender is shunted by the closure of the following path for the current: spring 233 (9), conductors 262, 234, spring 235 (9), conductor 263, brush b , terminal t , conductors 351, 319, spring 318 (3), conductor 320, segments of commutator A', brush 321 to ground. Upon the engagement of brush 321 with the fifth A' segment, and consequently upon the fifth de-energization of the stepping relay at the sender, the cut-off relay thereat is operated to open the fundamental circuit. This results in the de-energization of relay C'R', which at its right armature and back contact conductor 332 and spring 316 (3), moves the sequence switch S³ to position 4. In position 4, the trip magnet T'M' is energized over conductor 337 and spring 336 (4). When the fundamental circuit is again closed at the sender, the relay C'R' is again energized and locks up to conductor 315 over the circuit previously traced. At its armature and front contact and spring 305 (4) it moves the sequence switch S³ to position 5. In position 5 the circuit of magnet H is again completed as follows: free pole of the battery, magnet H, conductor 309, spring 310 (5), conductor 307, conductor 308, right armature and front contact of relay C'R', to ground. For each segment of the tens commutator B' passed over, the stepping relay at the sender is shunted over the circuit previously traced to spring 318, but instead of passing by way of conductor 320 and brush 321 to ground, now passes by way of conductor 323, commutator B' and brush 322, to ground. Upon six operations of the stepping relay, the number assumed being 455, the cut-off relay at the sender opens the fundamental circuit which results in the de-energization of the relay C'R'. The falling back of the right armature of this relay

opens the circuit of magnet H to arrest the movement of the shaft 350 with the tripped set of brushes in operative relation to the row of terminals containing the 10's digit of the wanted line. This armature at its back contact and spring 316 (5) moves the sequence switch S³ from position 5 to 6. When the fundamental circuit is again closed at the sender, the relay C'R' is again energized and locks up over the circuit previously traced. The closure of the right armature and front contact of relay C'R' moves the sequence switch S³ from position 6 to position 7 over the following circuit: free pole of the battery, magnet 300, conductors 303, 304, spring 305 (6), conductors 306, 307, 308, right armature and front contact of relay C'R', to ground. In position 7, the circuit of low speed magnet L is closed, and in attracting its armature 377 forces shaft 350 into engagement with the constantly rotating shaft 378. This circuit is as follows: free pole of the battery, magnet L, conductor 317, spring 310 (7) conductors 307, 308, right armature and front contact of relay C'R', to ground. Each time the brush 321 engages a segment of commutator C', the stepping relay at the sender is shunted over the circuit previously traced up to the spring 318, from thence it continues by way of conductor 320, segments of commutator C', brush 321, to ground. When the stepping relay at the sender has operated six times, the units digit of the called number being 5, the sender operates the cut-off relay which opens the fundamental circuit, which results in the de-energization of relay C'R' which at its right armature and front contact opens the circuit of magnet L to stop the elevating movement of the shaft 350 in engagement with the line 455 selected. The sender at the end of units selection causes its sequence switch to advance and close a circuit for the magnet 200 of the sequence switch S² (Fig. 2) over conductor 236 and spring 201 (9), whereupon the sequence switch moves to position 10. In passing out of position 9 spring 206 by opening its upper contact causes the release of the sending apparatus.

The A operator is assumed at this time to have inserted plug P' into jack J' (Fig. 1) thus causing the energization of relay 264 (Fig. 2), which at its front contact closes the following circuit to move the sequence switch S² from position 10 to position 11: free pole of the battery, magnet 200, conductors 265, 266, spring 267 (10), conductors 268, 246, 239, armature and front contact of relay 264, conductor 240, spring 268, to grounded spring 204.

The falling back of the right armature of the relay C'R' (Fig. 3) at the end of units selection moves the sequence switch S³ from position 7 to position 8 over the

following circuit: free pole of the battery, magnet 300, conductors 303, 304, spring 316 (7), conductor 332, right armature and back contact of relay C'R', to ground. Test relay TR (Fig. 3) is now connected to test brush b² over the following circuit: free pole of the battery, spring 324 (8), both windings of test relay TR, conductor 328, spring 330 (8), conductor 331, test brush b². If the line is busy, this test relay will not receive enough current for its energization due to the closure of a similar circuit in shunt of it at the other connector connected to this line, or due to the presence of an answering plug similar to P (Fig. 1) in the answering jack of such subscriber. Therefore the relay TR will not pull up its armatures. In position 8, the relay C'R' is energized over the following circuit: free pole of the battery, relay C'R', conductor 311, spring 346 (8), conductors 353, 351, terminal t, brush b, conductor 263, spring 235 (11), conductor 269, right armature and back contact of relay 247, conductor 243, left armature and front contact of relay 244 to ground. This relay was energized over the following circuit when the A operator inserted plug P' into jack J' and energized relay 264: free pole of the battery, relay 244, conductors 245, 246, 239, armature and front contact of relay 264, conductor 240, spring 268, to ground at spring 204. Relay C'R' at its right armature and front contact moves the sequence switch S³ to position 10 over the following circuit: free pole of the battery, magnet 300, conductors 303, 304, spring 305 (8), conductor 306, 307, 308, armature and front contact of relay C'R', to ground. When the connector sequence switch arrives in position 9, the following circuit is closed to energize the relay 334: free pole of the battery, conductor 354, relay 334, conductor 355, spring 330 (9), conductor 331, brush b², terminal t², through the cut-off relay of the selected line, to ground. This relay locks itself over conductor 356, spring 340 (9), its armature and grounded spring 341. In moving out of position 8, sequence switch S³ opened the circuit just traced for relay C'R' at spring 346 (8). Its right armature in retracting, closes the circuit of magnet 300 over spring 316 (10) to move the sequence switch to position 11. In this position the circuit of return magnet R is closed as follows: free pole of the battery, magnet R, conductors 338, 339, spring 340 (11), armature of relay 334 and grounded spring 341. The magnet R attracts its armature 357 causing the shaft 350 to move into engagement with the constantly rotating shaft 358 which drives the shaft downwardly. When the brush 322 reaches the segment Y', the following circuit is closed to drive the sequence switch from position 11 to position 16: free pole of the

battery, magnet 300, conductors 303, 304, spring 316 (11), conductor 342, segment Y', brush 322, to ground. Spring 316 being closed to conductor 342 in position 16 also, the sequence switch S³ immediately moves into position 17. In position 17 the interrupter 343 intermittently closes a circuit to relay C'R' by way of spring 344 (17) and conductor 311. The relay C'R' at its right armature and front contact applies ground to conductor 347 through the resistance 345. The intermittent application of this ground to conductor 347 causes the relay 248 (Fig. 2) to open and close its front contact to close a shunt around the left-hand high resistance winding H of relay 264, which in turn so increases the flow of current in the circuit leading back to the A operator's position that the calling supervisory relay S'R' is intermittently energized to flash the calling supervisory lamp S'L'. This indicates to the A operator that the line desired is busy, whereupon she so informs the calling party. Considering this operation more in detail, relay 237 was energized in parallel with relay 244 over the following path: free pole of battery, relay 237, conductor 361, left-hand armature and back contact of relay 247, armature and back contact of relay 242, conductors 238, 239, armature and front contact of relay 264, conductor 240, spring 268 (11) to ground at spring 204. The first application of ground to conductor 347 energizes the relay 242 (Fig. 2) over the following circuit: ground, right armature and front contact of relay C'R' (Fig. 3), conductor 308, resistance 345, spring 360 (17), conductor 347, terminal t', brush b', conductor 255, spring 233 (11), conductor 271, armature and front contact of relay 237, marginal ringing relay 242, ringing generator 280, to ground. The relay 242 opens the short circuit about relay 247 which is energized over the following circuit: free pole of the battery, relay 237, conductor 361, relay 247, conductors 238, 239, armature and front contact of relay 264, conductor 240, spring 268 (11), to ground at spring 204. Relay 247, by attracting its armature, short-circuits relay 237, which in falling back connects together conductors 270 and 271. The intermittent energization of the relay C'R' (Fig. 3) thus intermittently grounds conductor 347 and operates the relay 248 intermittently, which at its armature and front contact shunts out the left high resistance winding H of relay 264, thus increasing the current in the circuit of calling supervisory relay S'R' (Fig. 1) which causes the lamp S'L' to flash, thus indicating that the called line is busy. The A operator will thereupon inform the calling party of this fact and withdraw plugs P and P' from the jacks J and J'.

The withdrawal of plug P' from jack J' causes the deenergization of relay 264 (Fig. 2). The retraction of the armature of relay 264 causes the deenergization of relay 244.

5 The interrupter I intermittently connects ground to the right-hand armature of relay 244. Therefore when the relay 244 is deenergized the next grounding of its right-hand armature closes the circuit of relay CR by way of spring 272 (11). Relay CR at its left armature and front contact and spring 267 (11) moves sequence switch S^2 to position 12. In position 12 relay CR is held energized over the circuit: free pole 15 of battery, right winding of relay CR, conductor 210, spring 272 (12) which closes its lower contact before opening its upper contact, interrupter II to ground, until interrupter II breaks its contact which occurs about a second after interrupter I breaks its contact, these two interrupters being mounted on the same shaft. The relay CR then falls back and at its left armature and back contact and spring 227 (12) moves 25 the sequence switch to position 13. When interrupter I again closes its contact it energizes relay CR over the circuit previously traced, which relay at its left front contact and spring 267 (13) moves the sequence switch to position 15. Due to the deenergized condition of relay 244, the sequence switch moves directly out of position 15 and into 30 17 over the following circuit: free pole of the battery, magnet 200, conductors 265, 35 274, spring 275 (15), conductor 282, left armature and back contact of relay 244, to ground. In position 17 a circuit is closed for the return magnet R to restore the brush shaft 221. This circuit is as follows: free 40 pole of the battery, magnet R, conductor 276, spring 259 (17), conductor 260, to ground at spring 204. The magnet R by attracting its armature 277 forces the shaft 221 into engagement with the constantly rotating shaft 278 which drives the shaft downwardly. When the brush 227 contacts with segment Y, the following circuit is closed to drive the sequence switch to normal position: ground, spring 293 (17), brush 45 227', segment Y, conductor 279, spring 227 (17), conductors 228, 266, 265, magnets 200, to battery. When the sequence switch S^2 left position 14, the locking circuit of trunk relay 335 (Fig. 3) was opened at spring 259 50 (Fig. 2). This relay at its right armature and back contact and spring 349 (17) closes a circuit to drive sequence switch S^3 from position 17 into position 18. Due to the brush 322 engaging segment Y', the following circuit is immediately closed to drive the sequence switch to normal position: grounded brush 322, segment Y', conductor 342, spring 316 (18), conductors 304, 303, magnet 300, to battery. The apparatus is now 60 65 restored ready for use with another call.

Assuming now that the line 455 was idle when the connector was set upon the terminals t , t' , t'' , of such line. Referring to the diagram in the upper left-hand corner of Fig. 3, it will be seen that at this point the connector sequence switch S^3 is in position 8, it being remembered that when the fundamental circuit was opened at the sender upon the conclusion of the units selecting operation, the right-hand armature of $C'R'$ in falling back moved the sequence switch S^3 from position 7 to position 8. If the line be idle, the relay TR will become energized since it is not shunted by a connection to a multiple thereof at another connector or answering plug. The relay TR immediately locks itself up to the cut-off relay of the selected line at its right armature and front contact and conductor 380, and at its left armature and front contact moves the sequence switch out of position 8 over the following circuit: free pole of the battery, magnet 300, conductors 303, 304, spring 305 (8), conductor 352, left armature and front contact of relay TR, conductor 333, to ground at spring 341. The sequence switch immediately moves out of position 10, due to the deenergized condition of relay $C'R'$, the circuit being as follows: free pole of the battery, magnet 300, conductors 303, 304, 95 spring 316 (10), conductor 332, right armature and back contact of relay $C'R'$ to ground. The sequence switch immediately moves out of 11, due to the energized condition of the relay TR over the following circuit: free pole of the battery, magnet 300, conductors 303, 304, spring 305 (11), conductor 352, left armature and front contact of relay TR, conductor 333, to grounded spring 341, and into position 16 under the control of the contact A^3 closed between these positions in the manner well understood. When the sequence switch arrives in position 16, the selected line is signaled over the following circuit: ringing generator 280 (Fig. 2), marginal relay 242, armature and front contact of relay 237, conductor 271, spring 233 (11), conductor 255, brush b' , terminal t' , conductor 347, spring 360 (16), conductor 363, brush b^3 , terminal t' , line conductor b' , bell 364, condenser 365, line conductor a' , terminal t , brush b , conductor 366, spring 367 (16), conductor 351, terminal t , brush b , conductor 263, spring 235 (11), conductor 269, right armature and back contact of relay 247, conductor 243, left armature and front contact of relay 244, to ground. The bell 364 is intermittently operated in the well-known manner. When the subscriber at substation B^2 removes his receiver and closes a shunt about the condenser 365 and bell 364, the relay 242 which is marginal is energized in the well-known manner, and by opening its back contact removes the short circuit about relay 247. 125 130

This relay by attracting its left-hand armature shunts the relay 237, which in retracting its armature opens the ringing circuit and closes connection between talking conductors 270 and 271. The relay 247 at its right armature and front contact connects talking conductors 269, 281 together to complete the talking circuit. The relays 242 and 237 are thus deenergized and the relay 247 energized during conversation. The circuit for the relay 247 is as follows: free pole of battery, left armature and front contact of relay 247, said relay, conductors 238, 239, armature and front contact of relay 264, conductor 240, spring 268 (11), to grounded spring 204.

Talking current is supplied to the called party from the battery over the windings of repeating coil R'. The relay 248 is included in the talking circuit and energizes when the called party responds. In closing its armature and front contact it shunts out the high resistance winding H of relay 264 which causes the relay S'R' (Fig. 1) to be energized to extinguish the lamp S'L' indicating to the A operator that the called party has answered. Current is fed to the calling party from the battery over the windings of repeating coil R (Fig. 1). The subscribers may now converse.

Upon the hanging up of the receiver by the calling party at substation A⁴, the supervisory relay SR is deenergized and causes the lamp SL to light in the well-known manner. The A operator thereupon withdraws the plugs P and P' from the jacks J and J', respectively. The removal of the plug P' from the jack J' causes the deenergization of relay 264 (Fig. 2). This relay in retracting its armature deenergizes the relay 244. When the interrupter I next grounds the right armature of relay 244, the relay CR is energized over the following circuit: free pole of the battery, right winding of relay CR, conductor 210, spring 272 (11), conductor 250, to the right grounded armature of relay 244. The relay CR at its left armature and front contact closes the following circuit to move the sequence switch S² to position 12: free pole of the battery, magnet 200, conductors 265, 266, spring 267 (11), conductor 214, left armature and front contact of relay CR, to ground. In position 12 relay CR is held energized over the circuit: free pole of the battery, right winding of relay CR, conductor 210, spring 272 (12), interrupter II to ground, until interrupter II breaks its contact. The relay CR then falls back and at its left armature and back contact and spring 227 (12) moves the sequence switch to position 13. When interrupter I again closes its contact it energizes relay CR over the circuit previously traced, which relay at its left front contact moves the sequence switch to position 15. Due to

the deenergized condition of relay 244, the closure of the following circuit moves the sequence switch directly out of position 15 and into position 17: free pole of the battery, magnet 200, conductor 265, conductor 274, spring 275 (15), conductor 282, to ground at the left armature and back contact of relay 244. In position 17, a circuit is closed to drive the shaft 221 to normal position as follows: free pole of the battery, magnet R, conductor 276, spring 259 (17), conductor 260, to ground at spring 204. When the brush 227 reaches the segment Y, the following circuit is closed to drive the sequence switch to normal position: free pole of the battery, magnet 200, conductors 265, 266, 228, spring 227 (17), conductor 279, segment Y, to grounded brush 227'. The sequence switch S² and the selector S are thus restored to normal position.

When the sequence switch left position 14 spring 259 opened the locking circuit for trunk relay 335 at the connector (Fig. 3). This relay in retracting its right armature drives the sequence switch from position 16 into position 18 over the following circuit: free pole of the battery, magnet 300, conductor 303, spring 349 (16, 17), conductor 368, right armature and back contact of relay 335, to ground. In position 18 a circuit is closed to drive the connector brush shaft to normal position as follows: free pole of the battery, return magnet R, conductor 338, spring 348 (18), to ground. When the brush 322 in its return movement reaches the segment Y', the following circuit is closed to drive the sequence switch to normal position: grounded brush 322, segment Y', conductor 342, spring 316 (18), conductors 304, 303, magnet 300, to battery. Both the connector and the connector sequence switch S³ are now restored to normal position.

In order to keep the B operator informed of the progress of the call, certain lamps are provided at her position illuminated in certain positions of the sequence switch S². Lamp L is lighted when the B operator depresses the key 203 and causes the sequence switch S² to move into position 2, over the following circuit: free pole of the battery, lamp L, spring 284 (2 to 9 inclusive), conductor 285, interrupter III, to ground. It will be remembered that from positions 2 to 9 of the sequence switch S² the group selector S and the connector C are operating to connect with the wanted line, and that the sequence switch S² in moving out of position 9 by the opening of the engagement between spring 206 and its upper contacts, releases the sender at the end of units selection. Thus the lamp L intermittently flashes as long as the connection is being established and remains lighted continuously as soon as the connector is set upon

125

130

- the terminals of the selected line. Thus, if for any reason the switches are not properly set, the continued flashing of the lamp L will indicate this fact to the operator.
- 5 If, for any reason, the shaft 221 of the group switch S fails to become disengaged from the driving shaft 221, it will, upon reaching segment X , close the following circuit for the sequence switch magnet 200:
- 10 free pole of the battery, magnet 200, conductors 265, 274, spring 286 (1 to 8 inclusive), conductor 287, segment X , to brushes 226, 227, spring 293, to ground. The sequence switch is thus moved into position
- 15 9. In this position a lamp 288 is lighted over the following circuit: free pole of the battery, lamp 288, spring 286 (9), conductor 287, segment X , grounded brush 226. This lamp is preferably located on the racks
- 20 which carry the switches. The lighting of this lamp will indicate to an attendant that the switch has failed to operate properly, and the continued flashing of the lamp L will indicate this fact to the B operator, who
- 25 will then assign another trunk to the A operator. Similarly in the connector if the brush shaft 350 is not arrested before the brushes 321, 322 reach the segment X' , the following circuit is closed to drive the sequence switch into position 16: free pole of the battery magnet 300, conductors 303, 304, 377, 372, spring 373, conductor 374, segment X' , to grounded brushes 321, 322. The sequence switch in position 16 closes the
- 30 following circuit to light the lamp 375; free pole of the battery, lamp 375, conductor 376, spring 373 (16), conductor 374, segment X' , to grounded brushes 321, 322. The lighting of this lamp will indicate to an attendant that the switch has failed to act
- 35 properly.
- If the group switch S in position 7 fails to find an idle trunk, the test brush b^2 in leaving the last test terminal of the group opens the locking circuit of relay CR. This relay
- 40 at its left armature and back contact opens the circuit of magnet P , thus stopping the switch. The closure of its left armature to its back contact moves the sequence switch
- 45 out of position 7 into position 9. When the brush b^2 leaves the test terminal t^2 of the last trunk line in the group, the brush 226 engages a segment of the commutator Z . This results in the closure of the following
- 50 circuit for the sequence switch S^2 to drive the same into position 15: free pole of the battery, magnet 200, conductors 265, 266, 228, spring 227 (9 to 13), conductor 224, segment Z , brush 226, spring 293 (9). In
- 55 this position a circuit is closed to cause the lamp L to flash. This circuit is as follows: free pole of the battery, lamp L , spring 284 (15), interrupter IV to ground. This interrupter may be constructed differently
- 60 from interrupter III. This signal will in-

dicate to the operator that all the trunks are busy. She may then communicate this fact to the A operator over the order wire which operator then withdraws the plug P' from the jack J' . The withdrawal of the plug 70 deenergizes the relay 244 whose circuit is controlled at a front contact of relay 264. The relay 244 at its left armature and back contact closes the following circuit to drive the sequence switch S^2 into position 17, in 75 which the brush shaft 221 is restored: free pole of the battery, magnet 200, conductors 265, 274, spring 275 (15), left armature and back contact of relay 244, to ground. The restoring circuit for the brush shaft 80 221 is as follows: free pole of the battery, magnet R, conductor 276, spring 259 (17), conductor 260, to grounded spring 204. When the grounded brush 227 reaches the segment Y , the following circuit is closed to 85 drive the sequence switch from position 17 to normal: free pole of the battery, magnet 200, conductors, 265, 266, 228, spring 227 (17), conductor 279, segment Y , to grounded brush 227.

90

A lamp 283 is provided for each connecting circuit and becomes illuminated when the A operator plugs into the jack J' thereof, provided the operator has not depressed the key 203 to move the sequence switch S^2 95 to position 2. Thus, if the A operator inserts a plug into the wrong jack, the B operator will be made aware of it in this manner. This lamp would also be illuminated in case the sequence switch S^2 fails to completely restore after the A operator withdraws the plug P' from the jack J' , thus deenergizing relay 244, and by its continuous illumination serves as an indication of the failure of the apparatus to function 100 properly.

What is claimed is:

1. In a telephone exchange system, the combination with a manual board, calling subscribers' lines terminating in jacks therein, a cord circuit having an answering and a calling plug, a calling supervisory lamp associated with said cord circuit, a semi-automatic board, trunk circuits consisting of two wires only, said trunk circuits terminating at one end in jacks at said manual board and at the other end in selectors at said semi-automatic board, connectors at said semi-automatic board, called subscribers' lines terminating therein, means including 110 a sender at said semi-automatic board for setting said connectors on called lines, and means actuated by the busy condition of the called line to cause said supervisory lamp to flash intermittently.

115

2. In a telephone exchange system, the combination with a manual board, calling subscribers' lines terminating in jacks therein, a cord circuit having an answering and a calling plug, a supervisory lamp and re- 120

125

130

- lay controlling the same associated with said cord circuit, a semi-automatic board, link circuits consisting of two wires only, said link circuits terminating at one end in jacks 6 at said manual board and at the other end in selectors at said semi-automatic board, connectors at said semi-automatic board, called lines terminating therein, means for setting said connectors on called lines, 10 means whereby the said lamp is lighted upon the connection of the calling plug to a trunk jack, means for energizing said supervisory relay operated if the called subscriber responds to render said signal inert, 15 and means actuated by the busy condition of the called line for restoring the connector and for intermittently operating said supervisory relay to cause said supervisory lamp to flash.
- 20 3. In a telephone exchange system, the combination with a manual board, calling subscribers' lines terminating in jacks therein, a cord circuit having an answering and a calling plug, a telephone set adapted to be connected to said cord, a supervisory signal and a relay adapted to operate the same associated with said cord circuit, a semi-automatic board, link circuits terminating at one end in jacks in said manual board and 25 30 at the other end in selectors at said semi-automatic board, connectors at said semi-automatic board, called lines terminating in said connectors, a relay at said semi-automatic board having a high resistance winding in circuit with said supervisory relay, a relay at the semi-automatic board controlling a shunt about said high resistance winding, means for intermittently operating said relay if the called line is busy to cause the 35 40 said supervisory relay at the manual board to operate said signal intermittently.
4. In a telephone exchange system, the combination with a manual board, calling subscribers' lines terminating in jacks therein, a cord circuit having an answering and a calling plug, a telephone set adapted to be connected to said cord, a supervisory lamp and a relay adapted to shunt the same associated with said cord circuit, a semi-automatic board, link circuits terminating at one end in jacks in said manual board and at the other end in selectors at said semi-automatic board, connectors at said semi-automatic board, called lines terminating in 45 50 55 said connectors, means for setting said connectors on said lines, means whereby the said lamp is lighted upon the connection of the calling plug to a trunk jack, means for restoring the connector if the called line is busy, a relay at said semi-automatic board having a high resistance winding in circuit with said supervisory relay, a relay at the semi-automatic board controlling a shunt about said high resistance winding, means for intermittently operating said relay if the called line is busy to cause the 60 65 70 75 80 85 90 95 100 105 110 115 120 125 130

the called line is busy to cause the said supervisory relay at the manual board to flash said lamp.

5. In a telephone exchange system, the combination with a manual board, calling subscribers' lines terminating in jacks therein, a cord circuit having an answering and a calling plug, a telephone set adapted to be connected to said cord, a supervisory lamp and a relay adapted to shunt the same associated with said cord circuit, a semi-automatic board, link circuits terminating at one end in jacks in said manual board and at the other end in selectors at said semi-automatic board, connectors at said semi-automatic board, called lines terminating in said connectors, means for setting said connectors on said lines, means whereby the said lamp is lighted upon the connection of the calling plug to a trunk jack, means for restoring the connector if the called line is busy, a relay at said semi-automatic board having a high resistance winding in circuit with said supervisory relay, a relay at the semi-automatic board controlling a shunt about said high resistance winding, means for operating said relay when the called party responds to cause said supervisory relay to render said lamp inert, and means for intermittently operating said relay if the called line is busy to cause the said supervisory relay at the manual board to flash said lamp.

6. In a telephone system, a plurality of subscribers' lines, a manual board, means for establishing a connection between two of said lines including a cord circuit at said board having an answering and a calling plug, a trunk circuit terminating at said manual board in a jack adapted to receive said calling plug, an automatic switch, means for connecting said trunk to said switch and for setting the same on the called line, a signal in said cord, means for conductively separating but inductively uniting said trunk, a bridge across said trunk on the calling side of said means, a relay bridged across said trunk on the called side of said means, means for intermittently operating said last-mentioned relay when the called line is busy, means controlled by said relay for changing the resistance of said calling bridge, and means controlled by such change in resistance for operating said signal.

7. In a telephone exchange system, the combination with a manual board, calling subscribers' lines terminating in jacks therein, a cord circuit having an answering and a calling plug, a supervisory signal and a relay controlling the same associated with said cord circuit, a semi-automatic board, link circuits consisting of two wires only, said link circuits terminating at one end in jacks in said manual board, connectors

at said semi-automatic board, means for connecting said trunk to said connectors, called lines terminating at said connectors, the substations of such lines being provided
5 with switchhooks normally maintaining the telephonic circuits thereat open, means for setting said connectors on called lines, means whereby said supervisory relay is responsive to the actuation of said switchhook when
10 the called subscriber responds to operate said signal in one manner, and means actuated by the busy condition of the called line for restoring the connector and for intermittently operating said supervisory relay
15 to cause said signal to operate in another manner.

8. In a telephone exchange system, the combination with a manual board, calling subscribers' lines terminating in jacks there-
20 in, a cord circuit having an answering and a calling plug, a supervisory signal and a relay adapted to operate the same associated with said cord circuit, a semi-automatic board, link circuits terminating at one end
25 in jacks in said manual board and at the other end in selectors in said semi-automatic board, connectors at said semi-automatic board, called lines terminating in said connectors, the substations of such lines being
30 provided with switchhooks normally maintaining the telephonic circuits thereat open, means for setting said connectors on said lines, a relay at said semi-automatic board having a high resistance winding in cir-
35 cuit with said supervisory relay, a relay at the semi-automatic board controlling a shunt about said high-resistance winding, interrupters associated with said connectors, said interrupters being adapted intermit-
40 tently to operate said relay if the called line is busy to close said shunt to cause the said supervisory relay at the manual board to operate said lamp in one manner, and a circuit including the called line and switch-
45 hook thereat for operating said relay at the semi-automatic board to cause said signal to operate in another manner.

9. In a telephone exchange system, the combination of a manual board, calling
50 subscribers' lines terminating in jacks therein, a cord circuit having answering and calling plugs, a supervisory signal and a relay adapted to operate the same associated with said cord circuit, a semi-auto-
55 matic board, link circuits terminating at one end in jacks in said manual board and at the other end in selectors in said semi-automatic board, connectors at said semi-automatic board, interrupters associated there-
60 with, called lines terminating in said connectors, the substations of such lines being provided with switchhooks normally maintaining the telephonic circuit thereat open, means for setting said connectors on said
65 lines, a metallic circuit extending between

said manual and semi-automatic boards and including said supervisory relay, a relay at said semi-automatic board adapted to vary the resistance of said metallic circuit, a circuit for said relay controlled by 70 the called line switch-hook and a second circuit therefor controlled by said inter-
rupter, and means actuated by the busy condition of the called line for closing the circuit of said relay and interrupter. 75

10. In a telephone system, a called line, an A-operator's board, a B-operator's board, automatic switches, means for extending connection from said B-operator's board to said switches, means for controlling said switches for extending connection to said called line, a signal at said A-operator's board, a relay bridged across the conductors of the talking circuit at said B-operator's board, means for intermittently 80 varying the resistance of said bridge when said automatic switches attempt to make connection with a busy line, and means controlled by the variation of said current for intermittently operating said signal. 90

11. In a telephone system, a called line, an A-operator's board, a B-operators board, automatic switches, means for extending connection from said A-operator's board to said B-operator's board and from 95 said B-operator's board to said automatic switches, means controlled by said automatic switches for extending connection to the called line, a signal on said A-operator's board, a bridge across the conductors of the 100 talking circuit, means for increasing the flow of current through said bridge when said automatic switches attempt to make connection with a busy line, and means controlled by said increased flow of current for 105 operating said signal.

12. In a telephone system, a called line, an A-operator's board, a B-operator's board, automatic switches, means for extending connection from said A-operator's board to said B-operator's board and from 110 said B-operator's board to said automatic switches, means controlled by said automatic switches for extending connection to the called line, a supervisory signal on said A-operator's board, means for operating said signal to indicate when a called subscriber responds and when a disconnection is desired, a relay bridged across the conductors of the talking circuit at said B-operator's board, means for short-circuiting 115 part of the winding of said relay to thereby reduce the resistance of said bridge when said automatic switches attempt to make connection with a busy line, and means controlled by the change in resistance of said bridge for operating said signal. 120

In witness whereof, I hereunto subscribe my name this 4th day of June, A. D. 1915.

ALBEN E. LUNDELL
